HIS ATTORNEY.

UNITED STATES PATENT OFFICE

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY

SAFETY DEVICE FOR ROCK DRILLS

Application filed July 2, 1931. Serial No. 548,367.

This invention relates to rock drills, but more particularly to a safety device for fluid actuated rock drills, as for instance, those of the stoper type having rotation mechanism for rotating the working implement in the drill hole and in which the hammer piston of the drill and a rifle bar interlockingly engaged thereby serve as instrumentalities for rotating the working implement.

10 One object of the invention is to enable the rotation mechanism to be rendered promptly ineffective upon the occurrence of circumstances in the drill hole which would cause the working implement to become stuck and, 15 in consequence, cause the casing parts of the rock drill to rotate about the working implement.

Other objects will be in part obvious and in part pointed out hereinafter.

20 In the drawing accompanying this specification and forming a part thereof and in which similar reference characters refer to similar parts,

Figure 1 is a sectional elevation of so much 25 of a rock drill as will serve to illustrate the invention and a practical application thereof,

Figure 2 is a transverse view taken through Figure 1 on the line 2—2 looking in the direction indicated by the arrows, and

30 Figure 3 is a transverse view taken through Figure 2 on the line 3—3 looking in the direction indicated by the arrows.

Referring to the drawing, in which is shown an intermediate portion of a rock 35 drill of the stoper type, A and B designate the percussive and feeding elements respectively of the drill.

The percussive element comprises the usual cylinder C having a piston chamber D 40 wherein is arranged a reciprocatory hammer piston E for actuating the working implement (not shown) but which may extend into and be interlocked with suitable chuck mechanism (not shown). The chuck mechanism may, in turn, be conveniently interlocked with the hammer piston E in a well known manner to effect rotary movement of the working implement in accordance with the degree of rotative movement of the hammer piston.

The pressure fluid utilized for actuating the piston E may be distributed to the piston chamber D by a distributing valve such as that designated by F and arranged within a valve chamber G formed in this instance by 55 a pair of plates H and J at the rear end of the cylinder C. In the arrangement shown, the plate J is disposed between the cylinder C and the plate H and forms a closure for the rear end of the piston chamber D. The rear end of the plate J serves as a seating surface K for the wings L and O of the valve F.

The wing O of the valve in this instance controls the admission of pressure fluid to the 65 rear end of the piston chamber D through a rear inlet passage P in the plate J. The wing L controls the flow of pressure fluid from the valve chamber G through a front inlet passage Q located in the plate J and in the 70 cylinder C to convey pressure fluid to the front end of the piston chamber.

The rotation mechanism employed for imparting rotary movement to the piston E comprises a ratchet ring R having a bore S to 75 receive the head T of a rifle bar U which extends into the piston chamber D to interlockingly engage the hammer piston E in the usual manner. Disposed in the head T to oscillate therein are pawls V, two being 80 shown in the present instance, and said pawls are adapted to engage teeth W in the ratchet ring R. The pawls V may be provided with the usual springs X disposed in recesses Y in the head T and pressing against the pawls V 85 for actuating said pawls into engagement with the teeth W.

The ratchet ring R is encased by a head block Z which seats against the rear end of the plate H with one end and serves with its 90 other end as a seat for a cylinder b of the feeding element B. The head block Z also serves as a housing for a throttle valve c which is shown in this instance as being of the rotary type having a lever d for its manipulation. The throttle valve c has a central chamber e into which pressure fluid may be 95 constantly admitted from a suitable source of supply and in the wall of the throttle valve c are a series of ports f, g and h. The port h 100

is adapted to register with a supply passage *j* in the head block *Z* and the plate *H* and leading to the valve chamber *G*, and the port *f* may register with a passage *k* in the head block and opening into the cylinder *b*.

In addition to the cylinder *b* the feeding element used for advancing the rock drill towards the work in accordance with the penetration of the working implement into the work comprises a feed piston *o* of a well known type which may be provided with a rod *p* carrying at its lower or outermost end a pointer (not shown) but which may be adapted to seat upon a mine floor to support the drilling mechanism. The feeding cylinder *b* and the piston *o* may be of any well known construction in which the piston and cylinder are freely rotatable with respect to each other.

In accordance with the practice of the invention, means are provided for selectively rendering the ratchet ring *R* ineffective as an abutment for the pawls *V* when, owing to accidental circumstances in the drill hole the working implement tends to stick therein. The ratchet ring *R* is accordingly provided at its front and rear ends with annular flanges *q* and *r* respectively which seat loosely in annular grooves *s* and *t* in the plate *H* and in the head block *Z* in such wise that, in the absence of suitable restraining means, the ratchet ring may be rotated freely within said grooves.

On the outer peripheral surface of the ratchet ring *R* are a series of longitudinal extending teeth *u* similar in all essential respects to the teeth *W* to seat against a latch member *v* mounted pivotally on a pin *w*. The latch *v* is disposed in a recess *x* in the head block *Z*, and the ends of the pivot pin *w* are seated in the plate *H* and the head block *Z*.

The latch *v* comprises a dog or pawl *y* having an end surface *z* suitably shaped to conform to the side surfaces of the teeth *u* which it is intended to engage. On the opposite side of the pin *w* and integral with the pawl *y* is a wing *2* against one side of which acts a spring-pressed plunger *3* seated in a recess *4* in the head block *Z* to normally maintain the pawl *y* in engagement with a tooth *u*.

The arrangement is such that, owing to the pressure exerted against the wing *2* by the spring-pressed plunger *3*, the pawl *y* will be normally maintained in engagement or in position for engaging one of the teeth *u*. The pawl *y* may thus act as an abutment for the ratchet ring *R* to counteract the thrust of the pawls *V* against the ratchet ring *R* during a stroke of the piston, preferably during the rearward stroke and during which time the working implement is being rotated in the drill hole to change its position between successive blows of the hammer piston *E* thereagainst.

Means are provided for actuating the latch

v out of engagement from the teeth *u*. To this end the head block *Z* is provided with a chamber *5* to receive the head *6* of a plunger *7* acting against the wing *2* of the latch *v* and counter to the spring-pressed plunger *3*. The free end of the head *6* constitutes a pressure area *8* against which pressure fluid may act for actuating the plunger *7* in the direction of the wing *2*. Such pressure fluid may be conveyed into the chamber *5* by a passage *9* in the head block *Z* and wherewith the port *g* in the throttle valve *c* is intended to register.

Opening into the same end of the chamber *5* as the passage *9* is an atmospheric vent *10* which extends through the head block, the plates *H* and *J*, the cylinder *C* and a rotation handle *11* which may, as indicated, be secured to the cylinder *C*. The portion of the passage *10* located in the rotation handle *11* opens into a bore *12* in the rotation handle.

Disposed within the bore *12* is a guide bushing *13* which is retained fixedly in operative position in the bore *12* by a plug *14* threaded into the outer end of the bore *12*. The guide bushing *13* has a bore *15* to slidably receive a stem *16* of a valve *17* of the poppet type which is adapted to seat on a bevelled surface or seat *18* in the bushing *13*.

In the innermost end of the bushing *13* is a hollow plug *19* which serves as a seat for a spring *20* acting against the valve *17* to press said valve to the seat *18*. The portion *21* of the bore *15* adjacent the valve seat *18* is preferably enlarged so that when the valve *17* is in the open position pressure fluid flowing from the passage *10* through the hollow plug *19* into a chamber *22* wherein the spring *20* and the valve *17* are located may pass readily through the enlarged portion *21* to radial ports *23* in the bushing *13*.

The radial ports *23* open with their outer ends into an annular groove *24* in the periphery of the bushing *13*. The groove *24* in turn communicates with a passage *25* which extends through a depending grip portion *26* on the rotation handle *11* and which grip portion is intended to be grasped by the operator to hold the casing elements of the rock drill immovable and unaffected by the thrust imparted by the rotation mechanism of the drill.

Disposed on the outer end of the stem *16* of the valve *17* is a button *27* which, as will be observed, is in close proximity to the grip portion *26* so that it may be within easy reach of the hand whereby the grip portion *26* is grasped.

The operation of the device is as follows: With the throttle valve *c* in the open position, pressure fluid flows into the feeding cylinder *b* and the valve chamber *G* in the chamber *5* wherein the head *6* of the plunger *7* is located. The pressure fluid admitted into the feeding cylinder will act against the piston *o* and will move the drilling apparatus toward the work in a well known manner to

constantly maintain the piston E in such position with respect to the working implement as to assure an effective application of the blows of said piston to the working implement.

5 The pressure fluid admitted into the valve chamber G is distributed to the ends of the piston chamber D by the distributing valve F. Upon each admission of fluid into the rear end of the piston chamber D, the piston E is actuated forwardly against the working implement, and upon the reversal of the valve F pressure fluid is admitted into the front end of the piston chamber D to return the piston.

10 During such operation of the drilling apparatus and with the working implement capable of free rotation in the drill hole, the rifle bar U may rotate freely relatively to the ratchet ring R since, during the forward stroke of the piston E, the pawls V will merely pass over the teeth W. The piston E is therefore capable of delivering heavy blows of impact against the working implement.

15 Upon the return stroke of the piston E the pawls V will be pressed into engagement with the teeth W by the springs X. The piston E will then describe a partial revolution and, being suitably interlocked with the working implement, the working implement will also 20 be rotated to change its position in the drill hole for a succeeding blow of the hammer piston.

25 This operation of the hammer piston and the rotation mechanism may continue indefinitely as long as the working implement remains free to rotate within the drill hole. The rotation ratchet R will then be constantly maintained against rotative movement by the latch v and the latch v in turn is held in 30 this engaging position by the spring-pressed plunger 3.

35 During such operation, and which may be said to be the normal operation, the valve 17 is maintained in the open position by applying pressure against the button 27 so that the pressure fluid flowing into the chamber 5 may readily escape through the passages connecting the chamber 5 with the passage 25. The spring-pressed plunger 3 will therefore be unopposed.

40 In the event, however, that owing to breakage of the working implement or, as at times happens, the working implement enters a crevice in the rock and becomes stuck therein so that a thrust of sufficient force is imparted to the rock drill to jar the rotation handle out of the operator's hand the spring 45 will immediately act to close the valve 17. The pressure fluid thereafter flowing into the chamber 5 will promptly actuate the plunger 7 which in turn will trip the latch v out of engagement from the ratchet ring R and, although the piston E may thereafter continue its reciprocations, the ratchet ring R

will be released so that it may merely rotate with the rifle bar.

45 The casing elements of the drill will thereafter remain entirely stationary and in this way is avoided the danger of inflicting severe injury to the operator, such as is frequently caused by the rapidly rotating projecting parts of the rock drill.

50 After the working implement has again been freed or replaced the valve 17 may again be opened to exhaust the pressure fluid from the chamber 5, whereupon the spring-pressed plunger 3 will again actuate the latch v into engagement with the ratchet ring R which will then be held immovable to serve as a 55 fixed abutment for the pawls V.

I claim:

55 In a safety device, the combination with a rock drill having a hammer piston and rotation mechanism for the piston comprising a rifle bar wherewith said piston is slidably interlocked, a pawl carried by the rifle bar, of a ratchet ring to serve as an abutment for the pawl and being rotatable with respect to the rifle bar, a locking device for the ratchet 60 ring, a plunger for actuating the locking device out of engagement from the ratchet ring, a pressure area on the plunger and being in constant communication with a source of pressure fluid supply, an atmospheric vent 65 for the pressure area, valve means to control the vent and being normally held open to afford communication between the pressure area and the atmosphere, and means to close the valve means upon release thereof, thereby entrapping pressure fluid in the vent to act against the pressure area for releasing the locking device from the ratchet ring.

70 In testimony whereof I have signed this specification.

EARL B. LEAR.
